DESIGN FOR A BABY'S BIB

Laura V. Anderson, Glendale, Calif.

Application March 20, 1937, Serial No. 68,288

Term of patent 7 years

To all whom it may concern:

Be it known that I, Laura V. Anderson, a citizen of the United States, residing at Glendale, in the county of Los Angeles and State of California, have invented a new, original, and ornamental Design for a Baby's Bib, of which the following is a specification, reference being had to the accompanying drawing, forming a part thereof.

Fig. 1 is a plan view of a baby's bib showing my new design.

Fig. 2 is a front elevational view of said bib when tied together as when worn by a baby.

Fig. 3 is a rear elevational view of Fig. 2.

Fig. 4 is a side elevational view of Fig. 2 taken in the direction of the arrow 4.

I claim:

The ornamental design for a baby's bib as shown.

LAURA V. ANDERSON.
